APPARATUS FOR COATING ARTICLES

John H. Flink, Watertown, Mass., assignor to
 Hood Rubber Company, Inc., Watertown, Mass.,
 a corporation of Delaware

Application January 6, 1936, Serial No. 57,727

5 Claims. (Cl. 91—60)

This invention relates to apparatus for applying a coating to articles such as gloves or mittens made of textile material.

It is often desirable to provide gloves or mittens 5 of textile material with non-porous flexible facings of wear resisting material. As the application of the coating is preferably applied only to the working faces of the article so as to permit ventilation through other parts thereof, it becomes desirable to provide a method and apparatus whereby such incomplete coatings may be applied at low cost. Heretofore such coatings commonly have been applied by cementing or sewing patches of impervious or wear resisting material 10 over the desired area.

The principal objects of this invention are to provide simplicity of apparatus and efficiency and economy of operation, and to provide a neater and more secure coating on the article.

Other objects will appear from the following 20 description and the accompanying drawing.

Of the drawing:

Fig. 1 is a side view of the preferred form of apparatus used, the form clamping tongs being shown in open position with the textile gloves in place before the coating is applied, parts being broken away and parts shown in section to facilitate illustration.

Fig. 2 is a view of the same side of the same apparatus with the forms clamped together and the apparatus immersed in a dipping tank, the tank and part of the clamping collar being shown in section.

Fig. 3 is a cross-sectional view taken on line 3—3 of Fig. 2.

Fig. 4 is a rear view of a finished glove.

Referring to the drawing, the invention comprises assembling the glove or mitten on a dipping form, clamping the form against a masking structure and applying a coating over such portions of the textile material as are exposed. The forms are preferably used to mask each other and coated in pairs.

The preferred form of apparatus comprises a pair of forms 10, 11, each formed with a flat side 12, 13 of equal extent and corresponding in shape and area to the area of the article which is to remain uncoated. In the example shown the flat area is along the back of the glove. A pair of 45 gloves 14, 15 of woven cloth or other textile material are placed over the forms and their wrist portions are cuffed over the bases of the forms and tucked into the hollow interiors thereof as indicated at 16, 17.

In order to clamp the flat faces of the forms

together to prevent coating of the textile material over such flattened areas, and to support the forms, the forms are pivotally mounted as at 18, 19 to the ends of a pair of tongs 20, 21, to hold them in clamping relation as shown in Fig. 2 and when raised, as in Fig. 1, to permit the tongs being swung open on the pivot 22. A collar 23, formed with an aperture adapted to slide over the tongs 20, 21 and to hold them in clamped relation, may be raised to the position shown in Fig. 10 1 to release the tongs or to the position shown in Fig. 2 to clamp the tongs. The collar 23 is preferably formed on its outer face to the contour of the combined forms and when in clamping position its lower face contacts with the turned in 15 portions of the articles and clamps them against the forms so as to define the extent of the coating to be applied.

The coating may be applied in any desired manner as by dipping, spraying, etc., but it is preferred to deposit a coating by dipping the prepared forms in a dispersion or solution of the coating composition. Where rubber coatings are to be applied a solution of rubber in a volatile solvent, or a dispersion of rubber, either natural or artificial, in water, and containing vulcanizing agents, accelerators, age resisters, coloring and reinforcing pigments as desired, is prepared and the articles supported by the forms are dipped therein one or more times to provide the desired thickness of coating. Where natural or artificial dispersions of rubber are employed the articles may first be dipped in a coagulant of rubber such as calcium nitrate or acetic acid in a suitable solvent such as water, alcohol or acetone, or by the well known process of electro deposition the forms may be electrically charged as an anode and introduced into a dispersion with a cathode in the same circuit, in which case the coagulant may be dispensed with.

After the dipping or other coating operations have been performed and either before or after vulcanization of the coatings, which may be accomplished in any well known manner as by heating in dry air or steam or by contact with gases or 45 solutions of sulfur chloride or accelerators or the like, the forms with the textile articles thereon are separated and after vulcanization of the coatings the articles are removed from the forms.

I claim:

1. Apparatus for forming coatings over a portion of the surface of flexible contoured articles, said apparatus comprising a form adapted to fit within the article and having a flattened area corresponding to the area of the article to remain 55

- uncoated, and masking means adapted to cooperate with the flattened portion of the form to mask the portion of the article overlying the flattened portion.
- 5 2. Apparatus for forming coatings over a portion of the surface of textile articles, said apparatus comprising a pair of forms adapted to fit within a pair of articles and each having a corresponding flattened face, and means for clamping the forms with their flattened faces toward each other to mask the portions of the articles therebetween from coating material.
- 10 3. Apparatus for forming coatings over a portion of the surface of textile articles, said apparatus comprising tongs for supporting a plurality of forms, a form supported by each leg of the tongs, each form being adapted to fit within an article and having a portion of its face adapted to clamp the articles between adjoining forms to mask a portion of their surfaces, and means for clamping the forms in such relation.
- 15

4. Apparatus for forming coatings over a portion of the surface of textile articles, said apparatus comprising tongs for supporting a plurality of forms, a form supported by each leg of the tongs, each form being adapted to fit within an article and having a portion of its face adapted to clamp the articles between adjoining forms to mask a portion of their surfaces, and means adapted to clamp the articles around the mouth of the forms and simultaneously to clamp the 10 articles between the forms.

5. Apparatus for coating a portion only of the surface area of flexible contoured articles, said apparatus comprising means including a plurality of elements for supporting a plurality of articles 15 from within the articles, and means for holding the supported articles together so that a portion of the area of each article is masked from coating material.
